UNITED STATES PATENT OFFICE.

CHARLES FRANCIS JENKINS, OF WASHINGTON, DISTRICT OF COLUMBIA.

DESIGN FOR A GAITER.

60,684.

Specification for Design.

Patented Mar. 21, 1922.

Application filed July 21, 1921. Serial No. 486,608. Term of patent 3½ years.

To all whom it may concern:

Be it known that I, CHARLES FRANCIS JENKINS, a citizen of the United States, and resident of Washington, in the District of Columbia, have invented a new, original, and ornamental Design for Gaiters, of which the following is a specification, reference being had therein to the accompanying drawing.

In the drawing, a gaiter conforming to my novel design is shown in perspective, the opposite upper margins of the central portion of its body being approximately straight horizontal lines which in front curve upward and are continuous with the vamp margin and which near the rear, curve upward to join the front margins of a heel portion formed by extending the quarters far

above said body. Over the instep portion of the structure passes a loop connecting opposite margins of the body, and the gradually retreating margins of the upwardly extending quarters are similarly connected by three upwardly and forwardly inclined straps forming loops. Each of the four loops has on one side a button, and each is widened as it approaches the parts which it connects and in which it thus merges by gentle curves.

What I claim is:

The ornamental design for a gaiter, as shown and described.

In testimony whereof I hereunto affix my signature.

CHARLES FRANCIS JENKINS.
